SCAFFOLDING DEVICE

Lemaster C. McGill, Phillips, Tex., assignor to
Phillips Petroleum Company, a corporation of
Delaware

Application January 2, 1948, Serial No. 11

1 Claim. (Cl. 304—13)

1
This invention comprises a scaffolding device. An object of this invention is to provide a scaffolding structure and supporting framework therefor which eliminates the necessity of erection from the ground as with the conventional scaffold.

Another object of this invention is to provide a new and novel swinging scaffold for use on structures and especially structures which are of relatively small cross sectional dimensions with respect to their height, such as, for example, vertical cylindrical vessels or retorts widely used in oil refineries.

It is an object of this invention to provide a swinging scaffold by means of which various working levels for any point between the ground and the top of the structure may be established in a simple manner.

A more specific object of the invention is to provide a scaffold support in the form of a circular frame designed to be attached to the overhead nozzle of vertical cylindrical vessels such as a fractionation tower, for example.

Other and more detailed objects of the invention will be apparent from the following description of the embodiment thereof illustrated in the attached drawings as exemplary of the principles of this invention.

This invention resides in the combination, construction, arrangement and relative location of parts, all as will be hereinafter described.

In the accompanying drawings—

Figure 1 is a top plan view with a portion broken away of the circular mast attached to the overhead nozzle of a cylindrical vessel such as is commonly used in the oil industry;

Figure 2 is a side elevational view of this mast showing the upper end of the vessel and showing some parts in cross section;

Figure 3 is a cross sectional view through the circular track forming a part of the circular mast adjacent the bracing members;

Figure 4 is a front elevational view of a section of the swinging scaffold;

Figure 5 is a cross sectional view taken on the line 5—5 of Figure 2;

Figures 6, 7 and 8 are top plan side elevational and bottom plan views respectively of the structure for connecting adjacent sections of the circular rail forming part of the circular mast;

Figure 9 is an inside elevational view of a complete swinging scaffold section having extensible end sections; and

Figure 10 is a horizontal cross sectional view through the vessel showing the scaffolding in plan.

2
In the repair and maintenance of many elongated vertical structures such as, for example, the cylindrical vessels used as retorts and reaction chambers in oil refineries, the use of scaffolding from which the work may be carried on at various levels between the ground and the top of the vessel is required. Commonly, in the petroleum industry, vessels will have a cylindrical shape and a central top outlet. The vessels may reach very substantial heights and, as may be expected, in a large installation in the industrial atmosphere of a petroleum refinery, a great many details of maintenance require that the workmen obtain direct access to the vessels at any height. Since it is not practicable to equip each vessel with a scaffold, convenient demountable scaffolding must be provided and it is, accordingly, the basic advantage of the instant invention that a simple structure is provided for use on individual vessels as it is needed.

The structure disclosed below greatly reduces the costs and time consumption in providing the same advantages as the usual type of scaffolding. As will appear later, the amount of material involved in the scaffolding structure is greatly reduced by the use of the improvement herein disclosed as it is not necessary to build the scaffolding structure from the ground to the working level. It will also appear that the improvement herein disclosed is of such a nature that it may be used on vertical cylindrical vessels of any height and diameter with the limitation only that the specific structure disclosed with the vessel carry a centrally located outlet or take-off connection in its top head.

Referring first to Figures 1 and 2, it will be seen that the structure is illustrated in connection with a vertical cylindrical vessel 1 having a centrally located overhead take-off pipe or outlet 2 at its upper end. As is frequently the case, such an outlet is provided with a flanged coupling member 2' to which a similar member 3' of the adjacent pipe section 3 is attached thereto by a series of bolts. As is frequently the case and as illustrated in Figure 1, the pipe section 3 is similarly connected at its other end to continuing sections 3a, which after clearing the periphery of the vessel extend downwardly to some lower level as indicated in Figure 10, possibly nearly to the ground. The run of pipe 3a is illustrative of a type of obstruction adjacent the vessel for which provision must be made in providing a scaffolding from which the vessel may be worked upon at any circumferential point as well as any vertical point. As illustrated in Figure 10, such vessels are quite commonly provided with acces-

series of other kinds which will interfere with the scaffolding if provision to accommodate them is not provided. Thus, at 50 is illustrated a vertical ladder attached to the side of the vessel by means of supporting arms 51 and provided with an enclosing reinforced safety cage 52 within which the person using the ladder moves. In view of these and other types of obstructions including many auxiliary pipes commonly used with such vessels which prevent the use of continuous scaffolding for that reason as will appear later, special arrangements are required.

The overhead circular mast illustrated in Figures 1 to 8, inclusive, is, in accordance with this invention, adapted to be supported from the coupling bolts of the flange 2'-3'. As illustrated, there are provided a series of radial extending bars or arms 8^a adapted to be attached to the flanged coupling by means of its bolts as clearly illustrated in Figures 2 and 5. The outer ends of the bars 8^a are provided with slots to receive the bolts by means of which a pair of semi-circular members 5 and 6 are adjustably attached thereto. The ends of the members 5 and 6 are rabbed so that they may be engaged at a lap joint and secured together by a series of nuts and bolts 7, also illustrated in Figure 5. By means of this construction a continuous supporting ring of the necessary strength is supported from the flanged coupling 2'-3' and can be centrally located with respect to the pipe 2-3 by reason of the slot and bolt connections, illustrated.

Attached to the upper surface of the resulting supporting ring are a series of vertical web plates 8 which are equidistantly placed around the circumference of the ring and attached to the ring parts 5 and 6 in any suitable manner as, for example, by welding. Attached at their lower ends to each of the plates 8 on the opposite sides thereof are a pair of angle iron braces 9 secured to the plates 8 in any suitable manner as by bolts as shown or by rivets, welding and the like. The brace pairs 9 extend radially in an upward direction to a common level and are attached at their upper ends to the plates 10 on opposite sides thereof, again in any suitable manner but preferably by means of bolts. The plates 10 are secured to a circular track 11, see Figure 1, consisting of several arcuate sections 12, 12^a, 13 and 13^a comprising quadrants of the circular frame. These plates are preferably welded to the top flange of the I-beam and at two diametrically opposed points are secured together by a pair of cross braces 4 which may be in the form of single angle iron pieces equal to the outside diameter of the circular track 11 or each may consist of two pieces of angle iron substantially equal to the radius of the track and secured to a centrally located plate 4' illustrated in this case as a disc. At this point it may be noted that the various braces and reinforcing members are preferably attached together by means of nuts and bolts to facilitate erecting and dismantling the structure. By making the braces 4 of two parts detachably secured to the disc 4', these braces when demounted will be of less overall length and therefore better suited to storage than if made in a single piece.

The four arcuate track sections are connected together by a simple attaching means constructed to properly align the ends thereof. Thus, as is shown in Figures 7 and 8 the end of the track section 12, for example, has secured as by welding to the lower flange thereof an indexing lug 19 adapted to lie between a similar pair of lugs

20 on the adjacent end of the track section 13. Bolted to the upper flange of the section 12 at its end is a bar 17 arranged to overlie the adjacent upper flange of the section 13. It will be seen that this construction provides alignment for the mating ends of the sections 12 and 13 and also provides radial and transverse rigidity to the joint. This strength is further increased by the provision of a turn-buckle by means of which the ends of the sections are tightly drawn together in form locking connection. This construction includes a pair of studs 15 and 16 welded to the top of the sections 12 and 13 and between which extend a turn-buckle 18 by means of which the index ends of the sections 12 and 13 are tightly drawn together. In the case where the circular track 11 is made up of four arcuate sections 12, 12^a, 13 and 13^a, it will be apparent as suggested by Figure 1 that four splicing and securing structures of this type are required. When assembled, a continuous circular track is provided on which the scaffold supporting trolleys 21 may operate as suggested in Figures 2 and 3. These trolleys are provided with flanged rollers which operate on the upper faces of the lower flange of the circular track 11. The scaffolding is supported from these trolleys by means of the pulley blocks 22 and ropes 23.

The construction of the circular mast as thus described provides a very rigid and strong framework by means of which the loads applied thereto are equalized, distributed and transmitted to the supporting ring 5-6 and hence, in turn, to the vessel 1 through the overhead outlet 2.

The scaffolding itself is supported from the ropes 23 by means of the pulley blocks 24, two of which are preferably provided for each scaffolding section as illustrated in Figure 9. The lower pulley blocks 24 are connected to the scaffolding by bridles comprising a series of rods 25 as clearly shown in Figures 4 and 9.

The scaffolding proper consists as illustrated of main sections A and expandable or telescoping sections B mounted thereon. The sections A consist of a pair of longitudinally curved angle irons 27 attached together at spaced points by means of cross braces 28 which may be bolted, riveted or welded thereto as conditions dictate. Attached to the vertical flanges of the angle irons 27 are the reinforcing strips or bars 29 which give additional lateral rigidity to the platform framework. Extending vertically at the sides of this framework and attached to the angle irons 27 and reinforcing plates 29 preferably by welding are the vertical standards 30 which, in turn, are attached at their upper ends to the longitudinal hand rails 31. A series of gusset plates 32 are welded at the resulting corners of the framework to increase the strength thereof in a well known manner. In the form of structure illustrated the rods of the bridles 25 are secured to the reinforcing plates 32 but an equivalent attachment can be used. A reticulated floor 33 is secured in the platform framework and may be of any suitable non-slip material as, for example, an expanded metal grill.

As illustrated in Figure 9, the vertical flanges of the angle irons 27 are provided with longitudinal slots 34 in which are slidably mounted the transverse bars 35, see Figure 4. Mounted on the transverse bars 35 and arranged to nest within or telescope with the angle irons 27 are the spaced longitudinally curved angle irons 39 secured together by means of the cross braces 40. The ends of the rods 35 extend beyond the sides

of the platform framework of the main section A of the scaffold and receive the integral fittings 37 at the lower ends of the standards 36 of the expansion sections B. The fittings 37 fit over the ends of the rods 35 and are secured in place by means of nuts and washers, as shown. The upper ends of the standards 36 are connected by means of hand rails 38 and the platform of the expansion sections are completed by means of reticulated floors 41 which may also comprise grills of expanded metals or the like. The platform framework of the sections B is preferably of a length approximately equal to one-half of the length of the main section B so that when they are fully expanded as shown there will be considerable overlap, as illustrated in Figure 10, so that the sections B when extended will be sufficiently strong to support any normal weight to which they may be submitted. The sections B act as cantilevers and when fully extended their bottom frameworks remain telescoped with the bottom frame of the main section A with a distance equal to about one-quarter of the length of the main section as is clear from Figure 10.

The end standards 30 of the main section A are provided with a series of fixtures 39 and by means of which straps, chains or other closure members may be secured across the ends of the section to guard against a workman falling through the open end. Similarly, the end standards 30 of the section B are provided with similar fixtures 36' by means of which those ends will be closed or by means of which securing means may be attached to hold the adjacent ends of two scaffolding sections together in the position illustrated, for example, at the left of Figure 10 so as to, in effect, form a continuous rail.

It will be understood that the various parts of this structure will be made of suitable material to insure the necessary strength and are of course preferably made of structural steel.

In use, four scaffolding sections of the proper dimensions would be provided to form a continuous platform about the vessel at those vessels where there are no interfering balconies, manways, nozzles, connecting lines and the like. The parts would preferably be proportioned so that when the sections B are extended, the scaffolding is complete circumferentially, and when the adjacent ends are secured together as suggested above, a comparatively safe platform is provided. On the other hand, where the circumferential area of work is limited, it may be possible to complete it with the use of only one or possibly, at the most, two scaffolding sections. Where the work points are at different levels it is apparent that the various sections can be suspended at the different levels, and the work carried on simultaneously at these levels. In cases where the vessel is provided with permanent obstructions it is apparent that a section may be omitted and a partially continuous working level be provided in that region. Thus, by varying the manner in which the structure is used it is possible to provide a maximum working area subject to the lim- 60 65

itations of permanent obstructions throughout the vertical height of the vessel.

It is also within the scope of this invention to modify the scaffolding proper so as to eliminate the use of the extension sections B. In other words, one or more sections A of the proper dimensions can be employed without the refinement of the extensible sections B. In some cases, it can be preferable to provide each main section A with only one extension section B.

Those skilled in the art will recognize that the circular mast is arranged to provide maximum strength. The A braces 9 preferably extend at an angle of 45° and the inclusion of the X-brace 4 provides a very rigid structure when the A braces 9 are anchored at their lower ends as shown.

From the above description it will be apparent to those skilled in the art that the subject matter of this invention is capable of some variation in the details thereof and I prefer therefore not to be strictly limited to the illustrative embodiment employed herein but only as required by the claim.

What is claimed is:

A scaffold formed to be mounted on a vessel having a top central outlet, the scaffold comprising a central planar base flange, said base flange being formed for erection on said central outlet, supports extending upwardly and outwardly therefrom, a circular frame carried on the outer ends of said supports and forming the uppermost level of said scaffold, the said top outlet leading from said vessel being below the said uppermost level of said scaffold, a circular track carried by said frame and means for suspending a platform from said circular track.

LEMASTER C. MCGILL.
